US00D759148S

(12) **United States Design Patent**
Glynn et al.

(10) **Patent No.:** **US D759,148 S**
(45) **Date of Patent:** **** Jun. 14, 2016**

(54) **SPORTS VISUAL ZONE TRAINING APPARATUS**

(71) Applicant: **EPG Enterprises, LLC.**, Waseca, MN (US)

(72) Inventors: **Eugene P. Glynn**, Waseca, MN (US); **Eugene J. Glynn**, Waseca, MN (US); **Don E. N. Gibson**, Scottsdale, AZ (US); **Steven C. Elliott**, Macomb, MI (US); **Trevor Stewart**, Macomb, MI (US); **Bobby Luzzi**, Williamsburg, VA (US)

(**) Term: **14 Years**

(21) Appl. No.: **29/522,032**

(22) Filed: **Mar. 27, 2015**

(51) LOC (10) Cl. **16-06**

(52) U.S. Cl.

USPC **D16/300**; D16/309; D16/315; D16/314; D16/332

(57) **CLAIM**

We claim the ornamental design for a sports visual zone training apparatus, as shown.

DESCRIPTION

FIG. 1 is a top projected view showing my new design;
FIG. 2 is a bottom projected view thereof;
FIG. 3 is a front elevational view thereof;
FIG. 4 is a back elevational view thereof;
FIG. 5 is a top plan view thereof;
FIG. 6 is a bottom plan view thereof;
FIG. 7 is a right side elevational view thereof; and,
FIG. 8 is a left side elevational view thereof.

1 Claim, 6 Drawing Sheets
